Joseph Rosenthal, of New York, N.Y.
Assignor to Joseph Reckendorfer, of same place
Letters Patent No. 1229, dated April 3, 1860.

The schedule referred to in these Letters Patent and making part of the same.

To all whom it may concern:

Be it known that I, Joseph Rosenthal, of the City of New York, in the County and State of New York, have invented or produced a new and original design for a trade mark, for labels for lead pencils, and I do hereby declare that the following is a full and exact description of the same.

My design consists of the words "Eagle Pencil" and of the figure of an eagle standing beneath the printed words with his wings extended and head erect and turned toward the right, and of two flags, three arrows and a bunch of Olive.

In order more particularly to describe my new design, I will give its parts more in detail.

The mouth of the eagle is open and the tongue prominent. The

Dec. 1229

back of the neck exhibits two projections or curled feathers. Each pinion and wing is fully exhibited and are very nearly alike in apparent size, position, and action. The tail extends far below the other portions of the bird and inclines to the right - the observers right. The right foot of the eagle extends a little beyond the line of the body and grasps the three arrows.

The three arrows diverge considerably, each making an angle with the next of about 25° (Twenty five degrees). The staff of the flag on the left of the figure terminates very near the extremity of the wing and extends along parallel to the general line of the lower edge of the wing and pinion on that side but considerably lower. The flag depending therefrom is Bavarian and describes one fold or wave. The inner corner of its lower edge is rounded.

The left foot of the bird is within the outline of the tail. It grasps the olive in such manner that the stem projects a little beyond the outline of the tail toward the observers left while the foliage extends beyond the outline of the tail in the opposite direction to an extent equal a little less than half the length of the wing. The flag on the right (is that of the United States of America and hangs in one fold or wave like the opposite. The staff on this side (the observers right) extends considerably beyond the tip of the wing and carries a small eagle. Its lower end stands a little higher then the lower edge of the tail.

Having now fully described my new design, what I claim as my invention is the new trademark for lead pencils herein described, composed of the eagle with its several appurtenances as herein described and of the words Eagle Pencil combined in the manner and so as to produce the distinctive trade mark herein shown and described.
